UNITED STATES PATENT OFFICE.

SYLVESTER C. HOLTZ, OF SHELBY, OHIO.

LAND-ROLLER.

1,214,463.

Specification of Letters Patent. Patented Jan. 30, 1917.

Application filed August 22, 1916. Serial No. 116,393.

To all whom it may concern:

Be it known that I, SYLVESTER C. HOLTZ, a citizen of the United States, residing at Shelby, in the county of Richland and State 5 of Ohio, have invented new and useful Improvements in Land-Rollers, of which the following is a specification.

This invention relates to land rollers, and it has for its object to produce a device of 10 this class of simple and improved construction, the width of which may be varied so that while the device is constructed to operate on a wide swath or stretch of land, it may be collapsed to facilitate passage over 15 narrow roads and bridges and through gateways and the like.

A further object of the invention is to produce a sectional roller which may be readily extended or collapsed with slight exertion on the part of the operator. 20

A further object of the invention is to produce a sectional roller comprising a plurality of roller carrying frames, one of which is arranged in front while two others 25 follow behind, the rear frames being pivotally connected with adjusting bars which are pivotally connected with the front frame, means being provided for guiding the adjusting bars and for adjusting the 30 rear frames with respect thereto.

With these and other ends in view which will readily appear as the nature of the invention is better understood, the same consists in the improved construction and novel 35 arrangement and combination of parts which will hereinafter be fully described and particularly pointed out in the claims.

In the accompanying drawings has been 40 illustrated a simple and preferred form of the invention, it being, however, understood that no limitation is necessarily made to the precise structural details therein exhibited, but that changes, alterations and modifications within the scope of the claims 45 may be resorted to when desired.

In the drawings, Figure 1 is a top plan view showing the improved device in collapsed condition and with dotted lines 50 showing the rear roller carrying frames tilted preparatory to extending the same. Fig. 2 is a side elevation. Fig. 3 is a top plan view showing the device with the rear roller carrying frames in extended position. Fig. 4 is a transverse sectional view taken on 55 the line 4—4 in Fig. 3. Fig. 5 is a rear elevation of a portion of the machine.

Corresponding parts in the several figures are denoted by like characters of reference.

The front roller carrying frame A and the rear roller carrying frames B are all of similar construction, each having been shown as consisting of a rectangular frame having a cross bar 15 and provided at the ends thereof with downwardly extending 65 brackets 16 affording bearings for the pivot members 17 of the rollers 18. A draft member, such as a tongue 19, is attached to and suitably connected with the front frame A.

Mounted on the front frame A intermediate and about midway between the ends thereof is a rearwardly extending reach member 20 carrying at its rearward end a cross bar 21 which is provided near the ends thereof with slots 22 extending horizontally 75 therethrough. Triangular brackets 23 and 23' are secured adjacent to the top and bottom faces of the reach bar near the front end thereof, the bracket 23' being interposed between the reach bar and the top 80 face of the frame A, the cross bar 15 of the frame A, the reach bar 20 and the apices of the triangular brackets 23, 23' being connected together by a king bolt 24; a fastening member 25 extends through the bases of 85 the triangular frames and through the reach bar to assemble said parts. Adjusting bars 26 are connected with the rearward corners of the triangular frames by pivot members 27, said adjusting bars extending through 90 the slots 22 of the cross bar 21, said adjusting bars being pivotally connected with the rearward roller carrying frames B by bolts or pivot members 28 engaging the cross bars 95 15 of said frames B.

Each adjusting bar 26 carries a lever stand including a notched segment bar 29 with which a lever 30 is pivotally connected, said lever having a stop member 31 to engage the notches in the segment bar. Each 100 lever is connected by a link 32 with the frame B that is pivotally connected with the adjusting bar on which the lever is mounted to enable the frame B to be tilted or rocked in a horizontal plane by means of 105 the lever, as indicated in dotted lines in Fig. 1 of the drawings. A seat 33 for the driver or operator is mounted on the reach bar 20.

For the purpose of securing the roller 110 carrying frames B, B in adjusted position when extended or collapsed, there is pro-

vided a locking lever 34 which is fulcrumed on the cross bar 21 to the rearward of the driver's seat, said lever being provided with a stop member 35 engaging notches in a segment 36. Links or connecting rods 37 connect the lever 34 with the adjusting bars 26, said rods being connected with the lever at opposite sides of the fulcrum thereof. The notches, 38, in the segment 36 are arranged to be engaged by the stop member 35 when the roller carrying frames B are fully extended or fully collapsed, as the case may be, and it will be seen that the locking lever and connecting rods will serve to maintain the roller carrying frames in adjusted position at either limit of their respective movements.

The operation of this invention and the advantages thereof will be readily understood from the foregoing description taken in connection with the drawings. When the rearward roller frames are extended, as seen in Fig. 3, the inner ends of the rearward rollers may slightly overlap the forward roller, thus enabling the machine to cover a wide space of ground. When the parts are in this position, the levers 30 will be thrown forward with respect to the segment bars, as shown, and the adjusting bars will abut on the outer end walls of the slots 22. If it is desired to collapse the machine, the levers 30 are thrown rearward, thus tilting the frames B, throwing their inner ends rearward and their outer ends in a forward direction. When the machine advances, the rollers in endeavoring to straighten out will travel obliquely in an inward direction until the position illustrated in Fig. 1 in full lines is assumed, when the adjusting bars 26 will abut on the inner end walls of the slots 22. To expand the device, the levers are thrown rearward, tilting the frames B to the position indicated in dotted lines in Fig. 1, when the rollers in endeavoring to straighten out will travel obliquely in an outward direction until the position shown in Fig. 3 is assumed. The locking lever and related parts will serve to lock the roller carrying frames B securely against accidental displacement when in adjusted position.

Having thus described the invention, what is claimed as new, is:—

1. In a machine of the class described, a front roller carrying frame, pivotally supported adjusting bars, means whereby said bars are connected with the front frame, rear roller carrying frames pivotally connected with the adjusting bars, and means for adjusting the rear roller carrying frames about their respective pivots.

2. In a machine of the class described, a front roller carrying frame, a reach pivotally connected therewith, triangular brackets supported adjacent to the top and bottom faces of the reach and connected therewith, adjusting bars pivoted between the triangular brackets at the rearward corners thereof, and rear roller carrying frames pivotally connected with the adjusting bars. 65

3. In a machine of the class described, a front roller carrying frame, a reach pivotally connected therewith, triangular brackets supported adjacent to the top and bottom faces of the reach and connected therewith, adjusting bars pivoted between the triangular brackets at the rearward corners thereof, and rear roller carrying frames pivotally connected with the adjusting bars; in combination with lever standards on the adjusting bars, hand levers fulcrumed on the said standards, and links connecting the hand levers with the rear roller carrying frames. 75

4. In a machine of the class described, a front roller carrying frame, a reach pivotally connected therewith, triangular frames adjacent to the top and bottom faces of the reach and connected therewith, a cross bar at the rearward end of the reach, said cross bar having horizontal slots adjacent to the ends thereof, adjusting bars pivoted between the triangular frames at the rearward corners thereof and guided through the slots in the cross bar, rear roller carrying frames connected pivotally with the adjusting bars, and means for swinging the roller carrying frames about the pivots and for securing them in adjusted position. 85

5. In a machine of the class described, a front roller carrying frame, pivotally supported adjusting bars, means whereby said bars are connected with the front frame, rear roller carrying frames pivotally connected with the adjusting bars, means for adjusting the rear roller carrying frames about their respective pivots, and means for locking the adjusting bars in adjusted position. 100

6. In a machine of the class described, a front roller carrying frame, pivotally supported adjusting bars, means whereby said bars are connected with the front frame, rear roller carrying frames pivotally connected with the adjusting bars, means for adjusting the rear roller carrying frames about their respective pivots, means for limiting the movement of the adjusting bars, and means for locking the adjusting bars at the respective limits of their movement. 110

In testimony whereof I affix my signature.

SYLVESTER C. HOLTZ.
